Primary Examiner — Austin Murphy(74) *Attorney, Agent, or Firm* — Jun He Law Offices P.C.; James J. Zhu(57) **CLAIM**

I claims the ornamental design for smart glasses, as shown and described in FIGS. 1-8.

DESCRIPTION

FIG. 1 is a perspective view of the smart glasses showing our new design.

FIG. 2 is a front view of the smart glasses shown in FIG. 1. FIG. 3 is a rear view of the smart glasses shown in FIG. 1. FIG. 4 is a left view of the smart glasses shown in FIG. 1. FIG. 5 is a right view of the smart glasses shown in FIG. 1. FIG. 6 is a top view of the smart glasses shown in FIG. 1. FIG. 7 is a bottom view of the smart glasses shown in FIG. 1; and,

FIG. 8 is another perspective view of the smart glasses showing our new design.

The elements shown in broken lines form no part of the claimed design.
